SPORT SHIRT OR SIMILAR ARTICLE

Fredric Seelye, La Canada, Calif., assignor to Mabs Inc.,
Los Angeles, Calif., a corporation of California

Application June 20, 1957, Serial No. 46,673

Term of patent 3½ years

(Cl. D3—25)

FIG. 1.

Fig. 2 is a rear view thereof.

I claim:

The ornamental design for a sport shirt or similar article, substantially as shown.
